UNITED STATES PATENT OFFICE.

VICTOR GERARD, OF NEW YORK, N. Y.

DESIGN FOR WATCH-PLATES.

Specification forming part of Design No. 6,097, dated September 3, 1872.

To all whom it may concern:

Be it known that I, VICTOR GERARD, of the city and State of New York, have produced a new and original Design for Watch-Plates; and the following is a correct description thereof.

The quarter-plate *a* is shaped, as shown in the annexed drawing, with the exterior edge an arc of a circle from the center or arbor 1, and the inner edges as arcs of circles from the centers 1, 2, and 3. The central bridge is a compound curve of the form represented, so as to include the centers or arbors 1, 2, and 4.

These shapes given to the watch-plates are highly ornamental, and the teeth of the wheels and pinions are but little covered by the said plates.

I claim as my invention—

The design of the shape and configuration of the quarter-plate and bridge of a watch, as described and represented.

Signed by me this 19th day of June, 1872.
VICTOR GERARD.
